UNITED STATES PATENT OFFICE.

WILLIAM JACKSON, OF SORRELL, MISSOURI.

HAY-STACKER.

SPECIFICATION forming part of Letters Patent No. 671,022, dated April 2, 1901.

Application filed December 7, 1899. Serial No. 739,556. (No model.)

To all whom it may concern:

Be it known that I, WILLIAM JACKSON, a citizen of the United States, residing at Sorrell, in the county of Sullivan and State of Missouri, have invented a new and useful 5 Hay-Stacker, of which the following is a specification.

My invention relates to improvements in hay-stackers of that class which employ a 10 swinging frame movable in a vertical plane and on a horizontal axis for elevating and depositing the hay upon the rick or stack.

One object of the invention is to provide 15 improved means for easily adjusting an extensible ricker-frame and for locking the parts of said frame in their adjusted positions whereby the frame may be operated for discharging loads of hay upon the stack as it increases in height.

20 A further object is to provide means for adjusting the pitch or angle of one series of teeth with relation to the other series of teeth in the rake-head of the swinging ricker-frame, such adjustment serving to regulate the 25 discharge of the load from the rake-head at different periods in the elevation of the ricker-frame.

With these ends in view the invention consists in the novel combination and construction of parts, as will be hereinafter fully described and claimed.

In the drawings, Figure 1 is a perspective view of my improved hay-stacker, illustrating one embodiment of means between the base-frame and the swinging ricker-frame for the purpose of elevating the latter. Fig. 2 is a longitudinal sectional elevation through the hay-stacker shown by Fig. 1, illustrating the ricker-frame in a partly-raised condition. 35 Fig. 3 is a vertical transverse section through the ricker-frame in a plane at one side of the rake-head. Fig. 4 is a detail view of the means for operating and locking the adjusting-shaft for the extensible ricker-frame.

40 The same numerals of reference are used to indicate like and corresponding parts in each of the several figures of the drawings.

The base-frame of my hay-stacker is shown by the drawings as consisting of the side rail 45 10, the cross-rails 11, diagonals or braces 12, and the stakes 13, all of said rails being secured firmly together, while the stakes are fas-

tened, preferably, at one end of the frame, so as to be driven into the ground for holding the apparatus firmly in place against the pull 55 or strain of the elevating-rope.

In the embodiment of the invention shown by Figs. 1 and 2 of the drawings I employ a derrick-post 14, having a hinged connection at 14^a with the rear cross-head of the base-frame, and this post is provided at its upper free end with a cross-head 15. The derrick-post is held in place by the metallic brace-frame 16, which has its lower end suitably attached to the front cross-rail 11, while the 60 upper end of said brace-frame is confined on the post 14 by the clamp 17.

The extensible ricker-frame 18 is provided or equipped with the pivotal bars 19, the latter being disposed on opposite sides of the 70 base-frame and connected pivotally thereto—as, for example, by the bolts 20. Each pivotal bar 19 is connected with a side rail of the ricker-frame by a pair of clips 21 22, one of which clips is fastened to the bar 19, so as to 75 embrace the ricker-frame, while the other clip is made fast with the ricker-frame to slidably embrace the bar 19, whereby the ricker-frame is confined in slidable relation to the bars 19, which are pivotally attached to the base-frame. Each slide 21 is provided with an 80 eyebolt 23, and the slides composing the pair 22 are provided with journal-bearings 24, the latter being arranged in alinement with each other transversely across the ricker-frame. 85 An adjusting-shaft 25 is journaled loosely in these alined bearings on the clips 22, which are made fast with the pivotal bars 19, so that the shaft is supported in a stationary 90 position on the pivotal bars, while the ricker-frame has slidable relation to said shaft. This shaft is provided at its ends with short arms 26, the latter serving as a preferred 95 means for the attachment of the adjusting-cables 27 to the shaft. These cables are at the respective sides of the ricker-frame, so as to be fastened to the eyebolts 23 on the slides 21, which move with the ricker-frame, and thus the cables are adapted to be coiled 100 on the shaft 25 or to be uncoiled therefrom for the purpose of sliding the ricker-frame on the pivotal bars. With this adjusting-shaft I have combined means for conveniently rotating the same by hand and for

locking the shaft in its adjusted position, thus making provision for the adjustment of the ricker-frame and for holding said ricker-frame in said adjusted positions. As shown by Fig. 4, a ratchet 28 is made fast with the adjusting-shaft, at one end thereof. A feed-lever 29 is sleeved or otherwise connected loosely with this adjusting-shaft at a point adjacent to the ratchet, and this lever carries the feed-pawl 30, the latter being pivotally mounted on the lever in a position for engagement with the ratchet. The lever may be operated in one direction for the purpose of making the pawl turn the ratchet, which operates to partially turn the shaft 25 in its bearings, so as to coil the cables 27 on said shaft, thereby drawing the bolts 23 and the clips 21 toward the shaft for the purpose of extending the ricker-frame. A bracket-plate 31 is secured firmly on one of the clips or slides 22 at a point adjacent to the ratchet, and on this plate is fulcrumed a lever 32. Said lever carries a locking-pawl 33, which is arranged to engage with the ratchet for the purpose of locking the same against rotation under the strain or pull of the cables and the ricker-frame on the adjusting-shaft, thus maintaining the ricker-frame in its adjusted position with relation to the pivoted bars 19. The locking-pawl is disposed below the feed-lever and the feed-pawl thereon, so that the locking-pawl will be held against disengagement from the ratchet when the lever 32 occupies the position with relation to the feed-lever 29 shown by Fig. 4 of the drawings. The locking-pawl is made fast with its lever, and when the feed-lever and its pawl are raised the lever 32 may be manipulated to withdraw the locking-pawl from the ratchet, and when both of the pawls are free from the ratchet the weight or gravity of the ricker-frame or the pull of the elevating-rope thereon or the gravity of the drop-weight, presently described, may be availed of to slide the ricker-frame toward the pivots of the bars 19, thus shortening the ricker-frame. The rake-head of my hay-stacker is made fast with the outer end of the ricker-frame. This rake-head has a series of cross-rails 35 and two series of teeth, the teeth of one series being disposed at an angle with the teeth of the other series. The series of teeth indicated at 37 are secured fast to the cross-rails 35 36, so that the rails and the teeth are fast with the ricker-frame and the teeth substantially in alinement with said ricker-frame. The teeth forming the series indicated at 38 are adjustable by mounting them pivotally at 39 on the fixed teeth 37, so that the pivoted teeth may be disposed in positions at a right angle or at an obtuse angle to the fixed teeth. The pivoted teeth are connected one to the other for simultaneous adjustment through the medium of a connecting-bar 40, which is made fast to the teeth, and in connection with said series of adjustable teeth I employ a locking-rail 41, which is hinged or pivotally mounted, as at 42, on the cross-bar 35 of the rake-head. With this locking-rail adjusted to the position shown by full lines in Fig. 2 of the drawings the pivoted rake-teeth rest against the rail, so as to be held thereby in fixed relation and at right angles to the teeth 37; but an adjustment of the locking-rail 41 to the position shown by dotted lines in Fig. 2 permits the connected series of pivoted teeth to incline in a downward and forward direction, as indicated by the arrow in said Fig. 2, for the purpose of securing an inclined relation to the series of teeth 37 when the ricker-frame is elevated to its unloading position. This movement of the connected series of pivoted teeth is effected automatically by the weight or gravity of the load sustained by the rake-head, and the locking-rail may thus be adjusted for the purpose of discharging the load at either of two positions on the elevation of the rake-head with the ricker-frame. In the operation of forming the stack or rick it is desirable when the stack is small to discharge the load of hay before the ricker-frame and rake-head reach their highest points, and this is effected by moving the locking-rail 41 to the dotted-line position, thus permitting the pivoted teeth to be moved under the weight of the load; but as the stack increases in height the locking-rail is moved to its full-line position in Fig. 2, so as to restrain the connected teeth 38 from movement on their pivots, and thus the load is kept on the rake-head of the ricker-frame until the rake-head reaches practically its highest point.

As illustrated in Figs. 1 and 2, I employ an elevating rope or cable and a plurality of sheaves. A pair of sheaves 43 are attached to the rake-head, another pair of sheaves 44 are connected to the cross-head 15 of the derrick-post, and another pair of sheaves 45 is mounted on the front cross-rail 11 of the base-frame. An elevating-rope 46 has its ends fastened to the cross-head 15 of the guide derrick-post, and the strands of this rope are reeved through the sheaves 43, the sheaves 44, and the sheaves 45, both strands of the rope passing through the double sheave (shown by Fig. 1) at one side of the base-frame.

To assist in returning the swinging ricker-frame to its lowered position, I employ a drop-weight 47, which is fastened to a rope 48, the latter being carried through a guide 49 on the post 14 and connected loosely with the adjusting-shaft 25. With the ricker-frame in its elevated position after the load shall have been discharged therefrom the strain on the elevating-rope is slackened, and the drop-weight then acts on the pivoted ricker-frame to give an initial impulse thereto, so as to start said frame in a downward direction for returning the parts to their lowered positions, which enables another load of hay to be deposited on the rake-head.

Changes within the scope of the appended claims may be made in the form and proportion of some of the parts, while their essen-

tial features are retained and the spirit of the invention is embodied. Hence I do not desire to be limited to the precise form of all the parts as shown, reserving the right to vary therefrom.

Having thus described the invention, what I claim is—

1. In a hay-stacker, a base-frame having a derrick-post, in combination with an extensible ricker-frame pivotally connected to the base-frame, an adjusting-shaft for said ricker-frame and having a ratchet, a feed-lever on said shaft having a pawl engaging said ratchet, a lever supported independently of said shaft and having a rocking pawl to engage said ratchet, a rake-head at the outer end of the ricker-frame, and connections between the ricker-frame and the derrick-post, whereby said rake-head may be raised and lowered, substantially as described.

2. In a hay-stacker, the combination of a base-frame and a derrick thereon, with an extensible ricker-frame pivotally connected to the base-frame and having an adjusting-shaft, lever, and connections whereby said ricker-frame may be lengthened or shortened, a cord connected to said shaft and a guide in the derrick, said cord being weighted, a rake-head at the outer end of the extensible ricker-frame and tackles connecting said ricker-frame to said derrick whereby said rake-head and ricker-frame may be raised and lowered, substantially as described.

3. In a hay-stacker, the base-frame, the derrick-post hinged at its lower end to the base-frame and having the cross-head at its upper end, and the brace-frame connected at its lower end to the base-frame and clamped at its upper end to the derrick-post, the ricker-

frame pivotally connected to the base-frame 40 and having the rake-head at its outer end, and tackles connecting said ricker-frame to the cross-head on the derrick-post, substantially as described.

4. In a hay-stacker, a pivoted frame and 45 means to raise and lower the same and a rake-head on said frame, said rake-head having a series of fixed teeth, parallel cross-rails on the inner ends of said fixed teeth, a series of pivoted teeth adapted to move in unison, and 50 a locking-rail hinged on one of the cross-rails and adapted to be turned in one direction to engage the rear sides of the pivoted teeth and thereby limit the play of the pivoted teeth for the purpose set forth, substantially as de- 55 scribed.

5. In a hay-stacker, the combination with an extensible ricker-frame, and an adjusting-shaft therefor, of a ratchet fast with the shaft, a feed-lever loosely mounted on the shaft and 60 carrying a pawl which engages with said ratchet, and a lever supported independently of the shaft and provided with a locking-pawl also arranged for engagement with the ratchet, substantially as described. 65

6. In a hay-stacker, a rake-head provided with a series of fixed teeth, a series of movable teeth, and a locking-rail movable into and out of engagement with the movable teeth, substantially as described. 70

In testimony that I claim the foregoing as my own I have hereto affixed my signature in the presence of two witnesses.

WILLIAM JACKSON.
